Des. 195,593
Patented July 2, 1963

195,593

ELECTROSTATIC SEPARATOR FOR PARTICULATE MATERIALS

James Hall Carpenter, Jacksonville, Fla., assignor to
Carpco Research & Engineering, Inc., Jacksonville,
Fla., a corporation of Florida

Filed June 23, 1961, Ser. No. 65,703

Term of patent 14 years

(Cl. D55—1)

FIG. 1

FIG. 2

FIG. 3

FIGURE 1 is a front perspective view of an electrostatic separator for particulate materials embodying my new design;

FIGURE 2 is a left side view thereof; and

FIGURE 3 is a top plan view thereof.

The rear, not shown, is flat and plain, as indicated in FIGURES 1, 2 and 3.

I claim:

The ornamental design for an electrostatic separator for particulate materials, as shown and described.
